CLAIM

The ornamental design for a combined cutting board with detachable knife cleaner/sharpener, as shown and described.

DESCRIPTION

FIG. 1 is a front, top and side perspective view of the combined cutting board with detachable knife cleaner/-sharpener showing my new design;

FIG. 2 is a front elevational view thereof, the rear being a mirror image of the front shown in FIG. 2;

FIG. 3 is a left side elevational view thereof;

FIG. 4 is a right side elevational view thereof;

FIG. 5 is a top plan view thereof; and,

FIG. 6 is a bottom plan view thereof.

FIG.1

FIG. 2

FIG. 3

FIG. 4

FIG. 5

FIG. 6
